J. YOUNG.
RAILROAD CHAIR.

No. 22,685.

Patented Jan. 18, 1859.

Inventor
John Young

UNITED STATES PATENT OFFICE.

JOHN YOUNG, OF WEST GALWAY, NEW YORK.

RAILROAD-CHAIR.

Specification of Letters Patent No. 22,685, dated January 18, 1859.

To all whom it may concern:

Be it known that I, John Young, of West Galway, in the county of Fulton and State of New York, have invented a new and useful Improvement in Railroad-Chairs; and I do hereby declare that the following is a full, clear, and exact description of the same, reference being had to the annexed drawing, forming part of this specification, in the several figures of which similar characters of reference denote the same part.

Figure 1 is a plan of chair and rail in position. Fig. 2 is a top view of chair. Fig. 3 is a cross section of rail and chair. Fig. 4 is a top view of the yielding portion of chair. Fig. 5 is a vertical section on $y-y$ of Fig. 2. Fig. 6 is a side view of chair detached. Fig. 7 is a top view of sliding portion detached. Fig. 8 is a top view of spring portion of chair detached.

The nature of my invention consists in a peculiar construction hereinafter to be set forth for adapting the chair to the laying of rail on curves, the details being as follows:

This chair consists of two parts a b and a' , the former consisting of a double branched plate b , from whose arms arise the bearing pieces a . By drawing the ends e toward each other the inclinations of the bearing faces of a a' are altered, so as to press firmly

against two rails which depart from a straight line. The portion a' of the chair has an under bearing plate d , and an opening for the passage of the double branched plate b , as shown in Fig. 6. A wedge c drives the piece a' firmly against the rails, as shown in Fig. 3.

By this construction of chair the bearing faces of a are made to assume the requisite inclination to each other while by portion a' the rails are forced firmly against these opposite inclined bearers, thus firmly securing the ends of rails when a curved track is to be constructed.

There may be modifications of my construction. Therefore I do not design to confine myself to the precise devices shown.

I claim—

The combination of bearing surfaces a capable of forming any desired angle with each other, and the securing portion a' of the chair; substantially as, and for the purpose set forth.

In testimony whereof, I have hereunto signed my name before two subscribing witnesses.

JOHN YOUNG.

Witnesses:

JAMES STEWART,
JAMES YOUNG.
